JOHN H. ODENBACH, HERMAN GOLDMAN, AND WILLIAM C. HENRY, OF ROCHESTER,
NEW YORK, ASSIGNORS TO DOLOMITE PRODUCTS COMPANY, INC., OF ROCHESTER,
NEW YORK, A CORPORATION OF NEW YORK

ROTARY GRIZZLY

Application filed April 8, 1927. Serial No. 182,117.

This invention relates to a rotary grizzly of the general type comprising a series of disc-carrying shafts, the openings formed by the discs acting to separate stone coke or like material as it is fed therealong on top of the shafts.

One object of the invention is to provide a rugged and substantial arrangement of gearing between the power unit and the disc-carrying shafts, such that the machine will stand up and give efficient service for a long period of time, notwithstanding the excessive strain and wear to which it is subjected, while also making provision for driving the shafts at different speeds.

A further purpose of the invention is to afford a simplified arrangement of gearing and efficient means for assuring lubrication of all wearing parts of the gearing and bearings.

To these and other ends, the invention consists in the form and arrangement of parts that will appear clearly from the following description when read in conjunction with the accompanying drawings, the novel features being pointed out in the claims following the specification.

In the drawings:

Figure 1 is a side elevation, partly in section, of a machine constructed in accordance with a preferred embodiment of the invention;

Figure 2 is a plan view of the same;

Figure 3 is a sectional view taken vertically on the line 3—3 of Figure 1;

Figure 4 is a partial sectional view taken on the line 4—4 of Figure 3, and

Figure 5 is a diagrammatic view illustrative of the relationship between the worm gears and worms of a machine built in accordance with the invention and having a corresponding number of disc-carrying shafts.

The invention may be carried out in a variety of ways, and as an example of one practical adaptation, there is here disclosed a structure comprising a series of disc-carrying shafts 1, of which there may be any desired number, each provided with a disc 2 and forming the openings 3 through which

material is separated, as usual in accord with this type of machine.

The shafts 1 turn in bearings 4 forming part of a housing 5. The customary practice is to drive the disc-carrying shaft at the feed end of the machine at a minimum rate of speed and the disc-carrying shaft at the discharge end of the machine at a maximum rate of speed, the shafts in between having a uniform differential, and one of the accomplishments of this invention is to effect this constantly increasing speed of travel of the disc-carrying shafts by gearing of simple construction and with maximum wearing qualities. The parts now to be described are intended to bring this about.

Each disc-carrying shaft 1 has keyed thereon at its outer end a worm gear 6 that is engaged by a worm 7 slidably keyed on the driving shaft 8, so as to be fixed against relative rotation thereon and to have longitudinal play, the end thrust of each worm being taken by a bearing 9, which bearings are disposed intermediate the worms 7 and support the driving shaft 8. In order to operate the disc-carrying shafts at the necessary varying speeds, as set forth above, the worm gears 6 are of uniformly less diameter from the feed end of the machine toward the discharge end of the machine, as indicated clearly in Figures 4 and 5, and the driving shaft which carries the worm 7 is inclined with reference to a plane containing the axes of the worm gears and of the disc-carrying shafts 1, so that a constantly increasing speed of the disc-carrying shafts is had as the discharge end of the machine is approached. This arrangement affords a most rugged and durable driving gearing for a machine of this character, and it is equally important that adequate lubrication be insured to every part of the gearing at all times. This is accomplished in the following manner.

The worm gears 6 rotate in a chamber formed in the housing 5 by means of the outer side wall 10 and end walls 11 of the housing 5 and said chamber is divided into pockets by means of transverse overflow

walls located between the worm gears and extending preferably to points slightly beneath the centers of the gears, as shown in Figure 1. Referring to this figure, the machine is usually positioned at an incline to facilitate feeding of the mass to be separated toward the discharge end of the machine. The worm gears 6 rotate clockwise, each travelling in a bath of oil, preferably up to the level of the dotted line, and throw oil successively to the adjacent worm gears. In such fashion, the oil is continuously transferred until it reaches the worm gear at the feed end of the machine, which is the higher end. The oil filling into this particular pocket overflows the adjacent overflow wall 3 into the next pocket and so on into the successive pockets toward the discharge end of the machine. In this way, a more or less uniform level of oil is maintained in the various pockets and continuous circulation is effected to the several worm gears. At the same time, a certain amount of lubricant is transferred by the worm gears to the worms 7, causing them to be constantly lubricated, and in order to properly oil the bearings, the following construction is afforded.

13 designates a top or cover for the lubricant chamber, which may be attached to the housing in any suitable way and affords a top surface against which the lubricant is splashed by the worms 7. The lubricant is carried along the rib 13^a depending from the under surface of the top wall of cover 13 and drops into openings 14 of the bearings 9, whereby the latter are kept constantly in a state of lubrication. At the same time, a certain amount of oil flows from the worms 7 or is splashed by the worm gears 6 into openings 15 leading to the bearings 4.

The driving shaft is actuated from any suitable source of power, and to this end it may carry a gear 16 engaged and driven by a pinion 17 on the armature shaft of a motor 18, although power may be applied to the driving shaft 8 in any other way which may be found to be more convenient for any particular set-up.

50 The structure described affords a more durable and efficient arrangement than characterizes machines as heretofore constructed for this purpose and is of comparatively simple design with provision of means that makes certain of thorough lubrication of all wearing parts, thus contributing to the efficiency and wearing qualities of the machine. While the invention has been described with reference to a particular embodiment, it is not confined to the details or arrangements herein disclosed, and this application is intended to cover any modifications or departures coming within the purposes of the improvement or the scope of the following claims.

We claim:

1. In a rotary grizzly, the combination with a series of shafts, of a worm gear on each of said shafts, a driving shaft having a series of worms thereon engaging said worm gear, an oil chamber within which the worm gears rotate, transverse overflow walls in the oil chamber forming pockets, one for each worm gear, and acting to effect continuous circulation of oil to the various gears, bearings for the driving shaft intermediate the worms, said bearings having lubricating openings in their upper sides, and a cover for said chamber forming an enclosure for the gearing and acting to direct lubricant to the openings in said bearings. 70 75

2. In a rotary grizzly, the combination with a series of shafts, of a worm gear on each of said shafts, said worm gears being successively smaller from the feed end to the discharge end of the machine, a driving shaft inclined to the plane containing the shaft axes and having a series of worms thereon engaging said worm gears, an oil chamber within which the worm gears rotate, transverse overflow walls in the oil chamber forming pockets, one for each worm gear, and acting to effect continuous circulation of oil to the various worm gears. 85 90 95

3. In a rotary grizzly, the combination with a series of shafts, of a worm gear on each of said shafts, said worm gears being successively smaller from the feed end to the discharge end of the machine, a driving shaft inclined to the plane containing the shaft axes and having a series of worms thereon engaging said worm gears, an oil chamber within which the worm gears rotate, transverse overflow walls in the oil chamber forming pockets, one for each worm gear, and acting to effect continuous circulation of oil to the various gears, bearings for the driving shaft intermediate the worms, said bearing having lubricating openings in their upper sides, and a cover for said chamber forming an enclosure for the gearing and acting to direct lubricant to the openings in said bearings. 100 105 110

4. The combination with a series of adjacently arranged parallel shafts, of a lubricant-containing housing having a side wall, a series of bearings formed in the side wall for the aforementioned shafts, a worm gear mounted on each of said shafts within said housing, a drive shaft located within the housing and extending transversely of the first mentioned shafts, a series of worms slidably keyed on said drive shaft and each engaging one of the aforementioned worm gears, and a series of bearings for the drive shaft within said housing, one of said bearings being arranged between the ends of each two adjacent worms and acting to take the end thrust of one of them. 115 120 125 130

5. The combination with a series of adjacently arranged parallel shafts, of a lubricant-containing housing having a side wall, a series of bearings formed in said side wall for the aforementioned shafts, a worm gear mounted within the housing on each of said shafts, said worm gears being successively smaller from one end of the machine to the other, a drive shaft extending 10 transversely of the first mentioned shafts within said housing and inclined to a plane containing the axes of said shafts, a series of worms slidably keyed on said drive shaft, each engaging one of the aforementioned 15 worm gears, and a series of bearings located within said housing for the drive shaft, one of such bearings being located between the ends of each two adjacent worms and acting to receive the end thrust of one of said 20 worms.

6. The combination with a series of adjacently arranged parallel shafts, of a lubricant-containing housing having a side wall, a series of bearings formed in said side wall 25 for the aforementioned shafts, a worm gear mounted on each shaft within said housing, a drive shaft located within the housing above the worm gears and extending transversely of the first mentioned shafts, a series 30 of worms slidably keyed on the drive shaft and each engaging one of the aforementioned worm gears, and a series of bearings for the drive shaft located within said housing, one of said bearings being arranged 35 between the ends of each two adjacent worms and acting to take the end thrust of one of said worms.

In witness whereof, we have hereunto signed our names.
